No. 36,434.

Patented July 14, 1903.

UNITED STATES PATENT OFFICE.

FRED L. DAGGETT, OF SOMERVILLE, MASSACHUSETTS.

DESIGN FOR A CANDY-BOX.

SPECIFICATION forming part of Design No. 36,434, dated July 14, 1903.

Application filed May 16, 1903. Serial No. 157,487. Term of patent 7 years.

To all whom it may concern:

Be it known that I, FRED L. DAGGETT, a citizen of the United States, residing at Somerville, county of Middlesex, and State of Massachusetts, have invented a new, original, and ornamental Design for a Candy-Box, reference being had to the accompanying drawing, forming a part hereof.

The drawing shows the ornamental design for the candy-box in plan.

Having described my invention, what I claim as new, and desire to secure by Letters Patent of the United States, is—

The ornamental design for a candy-box as shown.

FRED L. DAGGETT.
